UNITED STATES PATENT OFFICE.

CARL ADOLF HARTUNG, OF BERLIN, GERMANY.

MEANS FOR WITHDRAWING STEAM FROM STEAM-ENGINES.

1,155,811.

Specification of Letters Patent.

Patented Oct. 5, 1915.

Original application filed March 28, 1911, Serial No. 617,356. Divided and this application filed May 14, 1912. Serial No. 697,205.

To all whom it may concern:

Be it known that I, CARL ADOLF HARTUNG, a subject of the King of Prussia, and residing at Berlin, Germany, have invented a 5 certain new and useful Means for Withdrawing Steam from Steam-Engines, of which the following is a specification.

The invention relates to steam engines, in which the heating steam is withdrawn from 10 the engine cylinder when the piston moves backward, the steam having been compressed by the piston to such an extent that its pressure exceeds by a small amount that in the pipe leading to the heating devices or radiators.

15 The invention consists in the provision of special withdrawal valves for the steam for heating purposes, independent of the usual admission and exhaust valves, which withdrawal valves are normally held closed by a 20 spring or its equivalent and are locked by a special valve gear during the working stroke of the piston. These valves are released during the return stroke of the piston, and 25 open when the pressure in the cylinder becomes a little greater than it is in the heating apparatus.

The present application is a division of 30 my copending application Serial No. 617,356, filed March 28, 1911.

The various features of the invention will be readily understood from an inspection of the accompanying drawings.

Figure 1 is a diagrammatic section showing 35 my device connected with a single stage steam engine; and Fig. 2 is a section through a particular form of withdrawal valve and its locking device.

Referring to Fig. 1 the cylinder of a 40 single stage ordinary engine has a piston *i*, and the usual admission valves *a*, *a*, at the top of the cylinder ends and exhaust valves *b*, *b*, arranged correspondingly below. Live steam is supplied through the admission 45 pipe *8* to the admission valves *a*, *a*. For withdrawing steam for heating purposes I provide special withdrawal valves *c*, *c*, from which the steam passes through the pipe *11* into the heating pipe. These withdrawal 50 valves *c*, *c* are constantly seated by the pressure of the steam for heating purposes and, if necessary, by an additional force, *e. g.*, a spring *n'* and are positively closed by valve gear *l* shortly before the admission valves 55 begin to open and are kept closed by this

gear during the expansion of the live steam in the cylinder. The pipe *d* leads from the exhaust valves *b* to the condenser or other exhaust. In this pipe is arranged a closure valve *e* diagrammatically represented as a 60 throttle valve. The rod *f* connects this valve with a controller, the cylinder *g* of which is connected by the pipe *h* with the heating system 37. The piston is thus subject to the pressure in the heating system 65 37. When the steam pressure in the pipe *h* rises it pushes the piston *9* forward against the action of the spring *10* and opens the valve *e* in the exhaust.

The cycle of operations takes place as follows:—When an inlet valve *a* opens shortly before the termination of the return stroke of the piston, the withdrawal valve *c*, located at the same end is closed by the valve gear *l*, while the withdrawal valve *c*, located 70 at the other end is released at the same moment, but is still kept seated by the excess pressure from the heating apparatus. The exhaust valves *b* are already open, and according to the pressure for the time being 75 in the heating apparatus the valve *e* has allowed a larger or smaller part of the operative steam to escape to the exhaust. After the direction of movement of the piston has been reversed and the valves *b* are 80 closed, the residue of steam is first compressed so that the pressure which is produced opens the withdrawal valve *c* and the steam issues through the same until the valve gear closes the withdrawal valve *c*, 85 shortly before the termination of the stroke. Then further compression takes place.

The withdrawal valves and closure members may be formed as desired. Fig. 2 shows 90 an illustrative form of the withdrawal valve in section. The head *m* of the cylinder *k* has formed therein the port *o* for the disk valve *p* which is pressed to the seat *q*, by the spring *n* and by the head of steam in the heating system 37. The disk valve *p* is provided with a relieving piston *r* slidably in the cylinder *s* and fast on the rod *w*. The space or chamber *t* behind the piston *r* communicates through the bore *u* of the rod *w*, with the cylinder *k*. The steam for heating 100 purposes passes out at *v* when the valve opens. The rod *w* is guided in the bearing *x*. Now when the steam presses against the valve disk *p* it simultaneously acts by way of the bore *u* in the opposite direction against 105 110

the relieving piston r . As the diameter of the valve disk p is larger than that of the piston r , the valve p with the piston r , will slide to the left in the bearing α until the mouth u' of the bore u enters into the bearing α and is thus closed. The steam shut off behind the relieving piston r then acts as a cushion. The disk p and piston r are moved back by the steam pressure of the heating pipe which, when the same is higher than the pressure in the cylinder, acts through the port v against the back of the disk p and closes the valve. The valve is closed and locked toward the end of the stroke of the piston by the slide 6 which is moved and controlled by suitable gearing directly or indirectly by means of the rod w . The slide 6 carries an antifriction roller 5 lying against the curved face 4 of a block 3 , attached by means of studs 2 on the piston 1 guided in the casing α . Between the rod w and the projection y of the piston 1 is interposed the spring n which abuts against a shoulder on the rod w . When the slide 6 is pushed upward the roller 5 runs up the curved face 4 and presses the block 3 and with it the valve disk p into the closed position. The spring n is of a strength sufficient to maintain the valve p seated under all pressures normally occurring in the cylinder k . It permits the valve to open however when the normal maximum pressure is exceeded and thus operates as a safety valve, although the valve as a whole may be held in closed position by the slide 6 .

I claim as my invention:—

1. A device for withdrawing steam for heating purposes from steam cylinders, comprising in combination, a withdrawal valve in communication with the steam cylinder, a hollow spindle therefor, a relieving piston on the latter to which steam from the cylinder has access through the hollow

spindle, a closure member for closing the bore in the spindle controlled by the movement of the spindle, and a device by which the withdrawal valve is held closed during the working stroke of the piston. 45

2. A device for withdrawing steam for heating purposes from steam cylinders, comprising in combination, a withdrawal valve in communication with the steam cylinder, a hollow spindle therefor, a relieving piston fast on the latter to which the steam from the cylinder has access through the hollow 55 spindle, a closure member for the bore of the spindle controlled by the motion of the spindle, a positively actuated slide, a roller journaled on the slide, and a plunger operatively connected to the said slide having a cam 60 face over which said roller runs on the displacement of the slide to close the withdrawal valve. 50

3. A device for withdrawing steam from steam cylinders, comprising in combination, 65 a withdrawal valve in communication with the steam cylinder, a hollow spindle therefor, a relieving piston fast on said spindle and subjected to the pressure of the steam cylinder through said hollow spindle, a closure member for the bore of the spindle controlled by the motion of the spindle, a positively controlled slide for holding the valve to its seat under normal pressure conditions, a roller journaled on the slide, a plunger 70 with cam bearing face for said roller adapted to be displaced by the latter during the travel of the slide and a spring interposed between the plunger and the valve spindle. 75

In testimony whereof I have signed my name to this specification, in the presence of two subscribing witnesses.

CARL ADOLF HARTUNG.
